UNITED STATES PATENT OFFICE.

ANTONIO S. ENNES, OF OAKLAND, CALIFORNIA, ASSIGNOR OF ONE-HALF TO JOAQUIN M. COSTA, OF MILL VALLEY, CALIFORNIA.

MILK-BOTTLE STOPPER.

1,199,166.

Specification of Letters Patent. Patented Sept. 26, 1916.

Application filed November 18, 1914. Serial No. 872,801.

To all whom it may concern:

Be it known that I, ANTONIO S. ENNES, a citizen of the United States, residing at Oakland, in the county of Alameda and State of California, have invented certain new and useful Improvements in Milk-Bottle Stoppers; and I do hereby declare the following to be a full, clear, and exact description of the invention, such as will 10 enable others skilled in the art to which it appertains to make and use the same.

This invention relates to new and useful improvements in milk bottle stoppers and has for its principal object to provide a 15 device which will effectively protect the neck of a milk bottle against any accumulation of dirt or dust within the mouth thereof.

Another object of the invention is to provide a cap which will be locked in place and 20 held firmly against accidental displacement.

A further object of the invention is to provide a metallic milk bottle stopper which is so constructed that the milk contained within the bottle at no time comes in contact 25 therewith.

With these and other objects in view, the invention consists in the novel combination and arrangement of parts which will be 30 fully set forth in the following specification and accompanying drawing, in which,

Figure 1 is a fragmentary sectional view of a milk bottle and stopper illustrating the same before the stopper is in place, Fig. 2 is a view similar to Fig. 1 illustrating the 35 stopper placed in position within the bottle, and Fig. 3 is a view similar to Fig. 1 illustrating the stopper in its locked position within the bottle neck.

Referring now to the drawing by characters of reference, the numeral 1 designates as an entirely a milk bottle of the usual construction which is formed with the usual neck 2 having formed at its upper end the bead 3. The coöperating bead 4 40 extends upwardly from the bead 3 and the inner edge of this coöperating bead becomes flush with the inner wall 5 of the bottle neck. This inner wall is inclined inwardly to form the shoulder 6, the use of which 45 will appear as the description proceeds.

The bottle stopper which is designated generally by the numeral 7 comprises the disk 8 which is concavo-convex in form and is formed at its periphery with the upstanding flange 9. The upper end of the upstanding flange is curved downwardly as

at 10 and is arranged to conform to the shape of the bead 4 hereinbefore referred to. In order to protect the contents of the bottle from the nipple of the stopper 7 there is provided the paper disk 11 which is of greater diameter than the disk 8 and is designed to overlie the face of the disk which is exposed to the contents of the bottle.

It will be apparent from the foregoing that in use the disk 11 is first placed in position on the bottle neck as illustrated in Fig. 1 and the stopper 7 is then placed on top thereof and forced inwardly into the position illustrated in Fig. 2. In this position it will be apparent that the disk will be forced into separate position so as to protect the contents of the bottle and prevent the same from coming in contact with the stopper so that any contamination due to the chemical action of the contents of the bottle against the metal will be eliminated. In order to lock the bottle cap in place, the raised portion of the disk 8 is pressed downwardly so that it expands and forces the side wall 9 into the bottle neck beneath the shoulder 6 to form a slight outward extension as at 12 which will effectively prevent the bottle stopper from being accidentally removed.

From the foregoing it will be apparent that a particularly simple and efficient bottle stopper is provided which will effectively retain the contents of a milk bottle within the same and prevent any dust or dirt from entering the mouth of the bottle and causing the contents thereof to be contaminated. It is also evident that any contamination of the contents is eliminated by the use of the paper disk 11 which effectively prevents the contents from engaging or coming in contact with the stopper and causing any chemical reaction which might injure the material within the bottle.

While in the foregoing there has been shown and described the preferred embodiment of this invention, it is to be understood that such changes may be made in the combination and arrangement of parts as will fall within the spirit and scope of the appended claim.

What is claimed is:—

The combination with a bottle neck having a bead adjacent its upper end, a co- 110 operating bead extending upwardly from the first named bead the inner wall of the

last named bead being inclined at its point of connection with the wall of the bottle neck to form a shoulder, of a metal stopper having a disk formed of metal, said disk 5 provided with a concavo-convex base, an upstanding peripheral annular flange formed around said base, the upper edge of said flange being curved downwardly over the upper bead of the bottle neck, the edge 10 of said flange resting upon the first named bead of the bottle neck and the base adapted

to be forced inwardly until the lower edges of the flange and base at their point of juncture are forced under the shoulder formed interiorly of the bottle neck, substantially as set forth. 15

In testimony whereof I affix my signature in presence of two witnesses.

ANTONIO S. ENNES.
